JAMES S. TORRENCE, OF LOS ANGELES, CALIFORNIA

THERAPEUTIC DEVICE

Application filed July 1, 1930. Serial No. 465,184.

My invention relates to and has for a purpose the provision of a therapeutic device of simple and durable construction, by which diseases and ailments responsive to 5 osteopathic methods of treatment, can be relieved and cured.

It is a further purpose of my invention to provide a therapeutic device particularly adapted although not necessarily, for private 10 use in the home, and embodying a support on which the patient is adapted to rest, and a vibratory applicator capable of being adjusted by the patient while resting on the support, to treat various parts of the body 15 with the utmost ease and dispatch.

I will describe only one form of therapeutic device embodying my invention, and will then point out the novel features thereof in claims.

20 In the accompanying drawings:

Figure 1 is a view showing in plan and partly broken away, one form of therapeutic device embodying my invention.

Figure 2 is a vertical transverse sectional 25 view partly broken away and taken generally on the line 2—2 of Figure 1 in the direction of the arrows.

Figure 3 is a transverse sectional view taken on the line 3—3 of Figure 2 and looking 30 in the direction of the arrows.

Figure 4 is a fragmentary view illustrating an operating member embodied in the device, and

Figure 5 is a detail view showing in vertical section one of various applicators which are adapted to be used with the device.

Referring specifically to the drawings in which similar reference characters designate similar parts in each of the several views, 40 my invention in its present embodiment comprises a table T the top 10 of which is supported in a horizontal elevated position by legs 11, and is provided with suitable upholstering 12 to form a cushioned support 45 on which the person to be treated is adapted to recline. Depending from the top 10 and secured to the legs 11, are side and end walls 13 and 14 respectively, which coact with the top in forming an enclosure for a mechanism by which an applicator A is adapted to

be mounted, vibrated and adjusted in a manner to be presently described.

This mechanism in the present instance comprises an electric motor M secured to and supported by a carriage C so that the shaft 55 15 of the motor extends horizontally. The shaft 15 extends into and is journaled in a transmission housing 16 secured to the carriage C by fastening members 17 and having an open side closed by a cover plate 18.

Fixed to the shaft 15 within the housing, 60 is a helical gear 19 constantly meshing with a second helical gear 20 fixed to a stub shaft 21 journaled in the housing and cover plate 18. Pivots connected to the gear 20 eccentrically of its axis, by a pin 22 is one end of a connecting rod 23, the opposite end of which is pivotally connected by a pin 24 to a vertically disposed shaft 25 slidably mounted in a sleeve 26 projecting upwardly 65 from the top wall of the housing 16.

The upper end of the shaft 25 projects 70 freely through a slot 27 extending longitudinally through the top 10 and its upholstering 12; and removably fitted on the free upper 75 end of the shaft is the applicator A which may be constructed of rubber, wood or any other suitable material, and formed in different shapes depending on the particular portion of the body to be treated. The applicator shown in Figures 1, 2, and 3 is intended for general use and is in the form of a flattened knob having an axial opening in which the shaft 25 frictionally fits so as to 80 detachably secure the applicator to the shaft. 85 The applicator A' shown in Figure 5 is intended for use in intestinal treatments and is in the form of a disk 28 having a domed central portion 29. It will be clear that with the motor M in operation, the shaft 25 90 will be rapidly reciprocated due to the eccentric connection of the rod 23 with the gear 20, so that vibratory movement will be imparted to the particular applicator applied to the shaft.

In the present instance the carriage C is 95 slidably mounted on, and guided for adjustment parallel to the length of the slot 27, by the angular side rails 30 of a rectangular frame 31, at the opposite ends of which are 100

journaled, rock shafts 32 and 32^a having eccentrically fixed thereto at their opposite ends, disks 33 and 33^a which rest upon angle bars 34 secured to the side walls 13 of the table so as to support the previously described mechanism from the table.

Journaled in bearings 35 in one of the side walls 13 of the table, is a rock shaft 36 having fixed thereto, arms 37 and 38, the arm 37 being connected by a link 39 to one of the eccentric disks 33, and the arm 38 being connected by a link 40 to one of the eccentric disks 33^a. Secured to the outer end of the shaft 36 is an operating member in the form of a hand lever 41 by which the shaft can be rocked to partially rotate the eccentric disks 33 and 33^a in one direction or the other through the medium of the links 39 and 40, to accordingly raise or lower the frame 31, carriage C and hence the applicator A, thereby varying the height of the latter above the top 10 of the table, to suit the requirements of the particular part of the body to be treated.

25 The lever 41 and hence the disks 33 and 33^a are adapted to be latched in any one of several selected positions of adjustment by means of a pawl 42 (Figure 4) slidably mounted in the lever and normally urged by a spring 43 into engagement with the teeth of an arcuate ratchet bar 44 extending through a slot in the lever 41 and secured by studs 45 to the side wall of the table. The pawl is adapted to be manually actuated to disengage the ratchet bar, by means of a button 46 fixed to the one end of a rod 47 extending through the lever 41 and secured to the pawl. The locations of the lever 41 and button 46 render them conveniently accessible for actuation by the person occupying the table, thus enabling the person while under treatment on the table, to vary the height of the applicator A as desired.

45 Rising from the carriage C is a post 48 slidably receiving a sleeve 49 formed on one end of an L-shaped arm 50 extending through a slot 51 in that side wall 13 of the table opposite the one on which the hand lever 41 is mounted. The other end of the arm 50 is secured to a tubular handle bar 52 slidably mounted on a rod 53 secured at its ends to brackets 54 fastened to the side wall 13 in any suitable manner. By sliding the handle bar 52 along the rod 53, it will be clear that corresponding movement will be imparted to the carriage C, and hence the applicator A likewise moved along the length of the slot 27 in the table, thus permitting any portion of the body of a person occupying the table to be subjected to the vibratory action of the applicator. It will also be clear that the post 48 and sleeve 49, while providing an operative connection between the carriage C and the arm 50 of

the handle bar 52, permit the vertical adjustment of the carriage and hence the applicator, as the post slides freely in the sleeve during such adjustment. Furthermore, the handle bar 52 is conveniently accessible for actuation by the person occupying the table, thus enabling adjustment of the applicator to any location along the length of the slot 27, and thereby permitting any portion of the person's body throughout its length to be subjected to the vibratory action of the applicator with the utmost ease and dispatch.

I have found in practice that a speed of less than 1000 vibrations per minute and approximately 750 vibrations per minute with about $\frac{1}{4}$ inch stroke of the applicator, is most effective for the relief of neurotic conditions and I consider this feature an important part of my invention.

Although I have herein shown and described only one form of therapeutic device embodying my invention, it is to be understood that various changes and modifications may be made therein without departing from the spirit of the invention and the spirit and scope of the appended claims.

I claim:

1. A therapeutic device comprising a table on which a person is adapted to recline, having a slot extending lengthwise with respect to the body of the person on the table, an applicator, means for mounting the applicator to project from said slot above the table, means for vibrating the applicator, and manually operable means for adjusting the applicator along the length of the slot including a slidably mounted handle bar accessible for manipulation by the person on the table.

2. A therapeutic device comprising a table on which a person is adapted to recline, having a slot extending lengthwise with respect to the body of the person on the table, an applicator projecting upwardly from said slot for engagement with the body of the person on the support, means for mounting the applicator for vibratory movement including a carriage slidably mounted beneath the table, means for moving the carriage to adjust the applicator along the length of the slot, and means for vibrating the applicator including a motor supported by the carriage.

3. A therapeutic device comprising a table on which a person is adapted to recline, having a slot extending lengthwise with respect to the body of the person on the table, an applicator projecting upwardly from said slot for engagement with the body of the person on the support, means for mounting the applicator for vibratory movement including a carriage, means for mounting the carriage beneath the table for sliding movement longitudinally of the slot, means for

moving the carriage to adjust the applicator along the length of the slot, means for vibrating the applicator including a motor supported by the carriage, and means for 5 adjusting the carriage mounting means to vary the height of the applicator above the table.

4. A therapeutic device comprising a table on which a person is adapted to recline, 10 having a slot extending lengthwise with respect to the body of the person on the table, an applicator projecting upwardly from said slot for engagement with the body of the person on the support, means for mounting 15 the applicator for vibratory movement including a carriage, means for mounting the carriage beneath the table for sliding movement longitudinally of the slot, means for moving the carriage to adjust the applicator along the length of the slot, means for 20 vibrating the applicator including a motor supported by the carriage, and means for adjusting the carriage mounting means to vary the height of the applicator above the 25 table, the last means comprising eccentrics journaled on the carriage mounting means and by which the latter is supported, an operating member, and means for rotating the eccentrics in response to movement of 30 the operating member.

5. A therapeutic device comprising a table on which a person is adapted to recline, having a slot extending lengthwise with respect to the body of the person on the table, 35 an applicator projecting upwardly from said slot for engagement with the body of the person on the support, means for mounting the applicator for vibratory movement including a carriage, means for mounting 40 the carriage beneath the table for sliding movement longitudinally of the slot, means for moving the carriage to adjust the applicator along the length of the slot, means for vibrating the applicator including a motor 45 supported by the carriage, and means for adjusting the carriage mounting means to vary the height of the applicator above the table, the last means comprising eccentrics journaled on the carriage mounting means 50 and by which the latter is supported, and means for rotating the eccentrics including an operating member accessible for operation by the person on the table.

JAMES S. TORRENCE.
